Primary Examiner — Richard Edgar*Assistant Examiner* — Taylor O Mortorff(74) *Attorney, Agent, or Firm* — ORBIT IP, LLP**CLAIM**

The ornamental design for a pressure washer, as shown and described.

DESCRIPTION

FIG. 1 is a front isometric view of a pressure washer showing my new design;

FIG. 2 is a rear isometric view thereof;

FIG. 3 is a front elevation view thereof;

FIG. 4 is a rear elevation view thereof;

FIG. 5 is top plan view thereof;

FIG. 6 is a bottom plan view thereof;

FIG. 7 is a right-side elevation view thereof; and,

FIG. 8 is a right-side elevation view thereof.
